CUTTER HEAD ATTACHMENT MEANS

David R. Locke, Bridgeport, Conn., assignor to Sperry Rand Corporation, New York, N.Y., a corporation of Delaware

Filed Jan. 14, 1963, Ser. No. 251,156
5 Claims. (Cl. 30—34.2)

This invention relates to new and useful improvements in cutter head attachment means for electric dry shavers.

In electric dry shavers wherein the cutter head is disposed within a recessed portion provided in the casing so that the exposed top surface of the cutter head is substantially flush with the exterior surface of the casing and where comb rollers are mounted adjacent the opposite side cutting edges of the cutter head on the opposite faces of the casing, various means have been used to detachably secure the cutter head to the casing. Since the exposed top surface of the cutter head is flush with the exterior surface of the casing, the cutter head cannot be readily removed from the recessed portion for cleaning or servicing by grasping the exposed surface thereof with one's hand. In the past therefore, casing sections such as hair pockets or hinged flap members have been mounted over or adjacent the cutter head and which sections had to be removed or opened to gain access to the cutter head. As an alternative to hair pocket sections, set screws or the like have been used to hold the cutter head to the casing or latching mechanisms have been used wherein the cutter head is partially ejected from the recessed portion by means operable from outside the casing.

It is an object of the present invention to provide novel attachment means for mounting a cutter head within a shaver casing.

Another object is to provide novel attachment means for mounting a cutter head within a shaver casing which also includes means for mounting comb rollers adjacent the side cutting edges of the cutter head.

Another object is to provide novel cutter head attachment means of relatively few and simple parts to facilitate the manufacture and assembly of an electric dry shaver.

It is a further object to provide novel means for mounting a cutter head flush with the exterior surface of the casing wherein access to the cutter head may be attained without resorting to removable hair pockets, flap hinge structure, set screws or ejectable cutter head latch mechanism.

The present invention contemplates a novel cutter head attachment means for an electric dry shaver wherein a mounting plate supports at least one cutter head unit within a recessed portion of a shaver casing and wherein the mounting plate has resilient side plates arranged on opposite sides of the cutter head. Each side plate has portions engaged by a detent projection provided on the side walls of the recessed portion which projections lock the cutter head to the casing. Means are also provided on the side plates for mounting comb rollers adjacent the side cutting edges of the cutter head. The side plates are movable toward and away from the walls of the recessed portion and may be moved clear of the detent projections by pressing the comb roller in the direction of the cutter head unit whereby the cutter head is readily removable from the casing.

The above and other objects and advantages of the present invention will appear more fully hereinafter from a consideration of the detailed description which follows taken together with the accompanying drawing wherein one embodiment of the invention is illustrated.

In the drawing:

FIG. 1 is a fragmentary elevational view of an electric dry shaver embodying the present invention with portions of the shaver casing and cutter head broken away;

2

FIG. 2 is an enlarged sectional view taken on the line 2—2 of FIG. 1;

FIG. 3 is a plan view of the electric dry shaver of FIG. 1 with the comb rollers removed;

5 FIG. 4 is a fragmentary plan view of the electric dry shaver of FIG. 1 with the cutter head removed from the casing;

FIG. 5 is a perspective view of the cutter head;

10 FIG. 6 is a sectional view taken on the line 6—6 of FIG. 5; and

FIG. 7 is a perspective view of one of the clamps which secures the cutter head units to the mounting plate.

Referring now to the drawing for a more detailed description of the present invention the upper portion of an electric dry shaver casing is generally indicated by the reference character 10 in FIG. 1. Electric dry shaver casing 10 is of the type having a premolded main body or cup section 11 formed of smooth hard plastic material within which section is disposed the usual motor (not shown). A cover section 12 is fitted over the cup section 11 and the peripheral edges of cover section 12 engage the peripheral upper edges of cup section 11 as seen in FIG. 1. The cover section 12 is provided with a recessed portion or cavity 14 in which is disposed a cutter head generally indicated by the reference character 15. Cover section 12 is secured to the cup portion 11 by screws 16 (FIGS. 2 and 4) which pass through the bottom wall 17 of recessed portion 14 and which screws are threaded into appropriate fittings (not shown) provided in the cup portion 11 beneath bottom wall 17. It is to be understood however, that the present invention which is to be hereinafter fully described is not limited to the particular electric dry shaver casing shown and is readily adaptable for use in other type shaver casings. The drawing has been simplified so as to show only those parts of the shaver casing 10 to illustrate an environment for the novel cutter head attachment means.

Cutter head 15 is disposed within recessed portion 14 of cover section 12 in such a manner that the upper exterior edges of the opposite end walls 18 of cover section 12 are substantially flush with the top surface (FIG. 1) of the cutter head 15 whereby the cutter head is protected from possible damage due to mishandling of the shaver. Opposite sidewalls 19 of cover section 12 adjacent recessed portion 14 are formed lower than the end walls 18 to expose the longitudinal side cutting edges of the cutter head 15 at each face of the casing. A comb roller 20 is disposed adjacent each side cutting edge of the cutter head at each face of the shaver in a manner to be hereinafter fully described. Angled detent projections 21 are formed on each sidewall 19 at the upper edge thereof and which detent projections 21 project toward each other on opposite sides of the recessed portion 14. Cutter head supporting seats 23 are also formed at each corner of the recessed portion 14 on the bottom wall 17 to support the cutter head 15 therein.

Cutter head 15, as illustrated, includes two individual elongated cutter head units 24 which are identical to each other and which units are of a well known construction. 60 The units 24 are disposed in side-by-side relationship on the rectangular base portion of a sheet metal cutter head mounting plate 25 which in transverse cross-section, as seen in FIG. 2, and has surfaces inclined toward the middle thereof. Each cutter head unit 24 includes an inverted U-shaped outer cutter 26 having opposite side-wall marginal portions rigidly secured to the arms of a U-shaped base spacer 27. An inner cutter 28 of the general type shown and described in U.S. Patent No. 2,793,430 issued May 28, 1957 to L. C. Carissimi is disposed within each outer cutter 26 and is urged against the outer cutter 26 by a leaf spring 29, partially shown in FIGS. 1 and 2 with the arms of leaf spring 29 connected to the opposite

ends of the inner cutter 28. Clamps 30 are arranged at opposite ends of the mounting plate 25 and have finger portions 31 engaged over portions of each base spacer 27 and on the underside of the mounting plate 25 to secure the cutter head units 24 to the mounting plate. Openings 32 are provided intermediate the ends of each base spacer 27 in alignment with openings 33 provided in the mounting plate 25. Motor driven oscillator arms 34 project through openings 35 in the bottom wall 17 of the cover section 12 and then through registered openings 32 and 33 to engage looped portions 36 of each leaf spring 29 in a well known manner, as disclosed in the mentioned patent, to bias the inner cutter 28 into cutting engagement with the outer cutter 26 and which oscillator arms 34 reciprocate the inner cutters 28 upon operation of the motor (not shown). Although the cutter head units 24 have been described in detail it will be readily apparent that the cutter head attachment means to be described is not limited to the particular type cutter head illustrated and described. It is also readily adaptable to a cutter head having one or more than two cutter units.

Mounting plate 25 which supports the cutter head units 24 as above described is provided with resilient side plates 37 and 38 respectively, and are illustrated in FIGS. 2 and 5 as formed integral with the opposite spaced and parallel longitudinal side edges 37a and 38a respectively of the rectangular base portion of mounting plate 25. It will be apparent however, to those skilled in the art that side plates 37 and 38 need not be integral with mounting plate 25 but may be attached thereto by any suitable fastening means. Side plates 37 and 38 extend upwardly and outwardly (FIG. 2) away from opposite edges 37a and 38a of mounting plate 25 and terminate in latch flanges 39 which latch flanges 39 are bent toward each other in the direction of the cutter head units 24. Ear portions 40 are provided at the opposite ends of each side plate and which ear portions are bent inwardly at a right angle to the side plate and project upwardly to approximately the top surface (FIG. 2) of the cutter head 15. An aperture 41 is provided in each ear 40 to receive one end of a comb roller 20. Comb roller 20 is of hollow construction and has a corrugated outer surface. Movable pins 42 project from opposite ends of comb roller 20. Each pin 42 is urged outwardly of the roller by a spring 43 and a circular flange 43a is provided on each roller located within the hollow roller (FIG. 6) to prevent the pin from leaving the roller. Another circular flange 44 is provided on the free end of each pin 42 and which flange 44 abuts against an adjacent ear portion 40. A comb roller 20 is mounted on each side plate 37 and 38 between spaced ears 40 by inserting the free end of pin 42 into an aperture 41 of the ear and by applying slight pressure in the axial direction of the inserted pin 42 whereby the pin 42 on the opposite end of the comb roller may be snapped into the aperture on the adjacent ear 40.

The cutter head 15, as above described, is mounted on the shaver casing by inserting it into the recessed portion 14. The resilient side plates 37 and 38 compress inwardly toward each other as the outer surfaces of each plate engages a detent projection 21 on the spaced sidewalls 19 of the recessed portion 14. Latch flanges 39 snap outwardly and under along the angled surface of each detent projection 21 as the four corners of the mounting plate 25 engage seats 23 on the bottom wall 17 of recessed portion 14. Projections 21 engage over flanges 39 of each side plate and the cutter head 15 is securely detented to the shaver casing within recessed portion 14. Cutter head 15 is readily released from the recessed portion 14 by pressing either comb roller 20 in the direction of its adjacent cutter head unit 24 (as shown on the right in broken lines in FIG. 2) whereby the latch flange 39 of side plate 38 beneath the pressed comb roller 20 is moved inwardly toward its adjacent cutter head unit and clear of its detent projection 21. The latch flange 39 on

the opposite side plate 38 is at once cammed (as shown in broken lines on the left in FIG. 2) against and then clear of its detent projection thereby releasing the cutter head from the recessed portion 14.

It is apparent from the foregoing that the novel cutter head attachment means has many advantages in use. One advantage is that removable hair pocket sections or the like or cutter head ejection mechanisms for gaining access to the cutter head are eliminated from the casing structure while casing structure is still provided for protecting the cutter head. An additional advantage is the simplicity of the attachment mechanism which is formed integrally with the cutter head mounting plate and which also provides means for mounting comb rollers thereon instead of attaching the comb roller to the casing.

Although one embodiment of the present invention has been illustrated and described in detail, it is to be expressly understood that the invention is not limited thereto. Various changes can be made in the design and arrangement of parts without departing from the spirit and scope of the invention, as the same will now be understood by those skilled in the art.

What is claimed is:

1. A cutter head attachment means for an electric dry shaver, comprising
  - (a) a casing having exterior wall portions defining a recessed portion in said casing,
  - (b) a cutter head disposed in said recessed portion,
  - (c) said cutter head having a cutting surface exposed in said recessed portion and bounded by said exterior wall portions,
  - (d) spaced detent projections on said casing adjacent said recessed portion, and
  - (e) resilient latch means carried by said cutter head engaged by said spaced detent projections to lock said cutter head to said casing,
  - (f) said latch means having a portion projecting out of said recessed portion,
  - (g) said projection portion of said latch means being movable under pressure from without said casing to unlock said latch means from said detent means to release said cutter head from said recessed portion of said casing.
2. Cutter head attachment means for an electric dry shaver, comprising
  - (a) a casing having a recessed portion formed therein,
  - (b) a cutter head disposed in said recessed portion,
  - (c) said cutter head including at least one cutter head unit having an inner and an outer cutter,
  - (d) a mounting plate having a pair of spaced side edges,
  - (e) means for securing said cutter head unit to said mounting plate,
  - (f) a pair of resilient side plates extending from said pair of spaced side edges of said mounting plate,
  - (g) latch means on said side plates, and
  - (h) detent means formed on the casing adjacent said recessed portion to engage said latch means to lock said cutter head to said casing within said recessed portion.
3. The cutter head attachment means of claim 2, wherein
  - (a) spaced ear projections are provided on each side plate,
  - (b) a roller comb mounted on and between each pair of said ear projections to lie adjacent a side cutting edge of the cutter head at each face of the casing, and
  - (c) said latch means and detent means being disengagable upon movement of one of said roller combs and its side plate in the direction of the adjacent side cutting edge of the cutter head.
4. Cutter head attachment means for an electric dry shaver, comprising
  - (a) a casing having a recessed portion formed therein,

- (b) a cutter head disposed in said recessed portion,
  - (c) said cutter head including at least one cutter head unit having an inner and an outer cutter,
  - (d) a rectangular mounting plate for supporting said at least one cutter head unit,
  - (e) a pair of spaced resilient side plates extending from a pair of spaced and parallel side edges of the rectangular mounting plate,
  - (f) latch flanges on each of said side plates, and
  - (g) detent projections on the walls of said recessed portion engaging each of said latch flanges to lock said cutter head to the casing within said recessed portion,
  - (h) either of said pair of latch flanges being movable away from its detent projection under manual pressure applied thereto whereby the other of said pair of latch flanges is released from its detent projection.
5. The cutter head attachment means of claim 4, 20 wherein,
- (a) spaced ear projections are formed on the opposite ends of each side plate,

- (b) a roller comb mounted on and between each pair of spaced ear projections to lie adjacent a side cutting edge of the cutter head, and
- (c) either of said latch flanges being disengageable from its detent projection by movement of the roller comb and its side plate in the direction of the said adjacent side cutting edge of the cutter head.
